UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

PROCESS FOR MAKING RAIL-JOINT BARS.

1,172,654.

Specification of Letters Patent. Patented Feb. 22, 1916.

Application filed May 27, 1912. Serial No. 700,106.

To all whom it may concern:

Be it known that I, BENJAMIN WOLHAUPTER, a citizen of the United States, residing at New Rochelle, in the county of Westchester and State of New York, have invented 5 certain new and useful Improvements in Processes for Making Rail-Joint Bars, of which the following is a specification.

This invention relates to an improvement 10 in rolling processes for metal bars, and more particularly to a rolling process specially designed for the production of a rail joint bar having a base section whose central portion is crowned or raised to provide a central rail seat or base bearing 15 for the ends of the rails, at the center of the joint, while the remaining portions of the base section of the joint bar are out of contact with the bottoms of the rails. 20 To this end the invention contemplates a practical, expeditious and economical method of producing rail joint bars with central crowned, or raised, seats for the rail ends, entirely by a novel manipulation 25 of the metal in the bar through the medium of roll-passes, so that after the bar is cut into rail joint lengths it is only necessary to bend or fold the base section of the bar into 30 its operative plane by any suitable means such for instance as by a press or a bulldozer.

While various instrumentalities may be utilized in carrying out this invention and various designs of rolls and roll-passes may 35 be adapted to the making of bars according to the present invention, one of the ways in which the process may be carried out in a practical manner is suggested in the accompanying drawings, in which—

40 Figure 1 is a sectional elevation of a pair of rolls of a rolling mill designed to provide two final finishing passes for giving to the bar such reductions, distribution of metal, and form as contemplated by the present invention. Fig. 2 is a sectional view of a portion of a folding machine or 45 press that may be employed in the final step, after reheating of the bar, of folding or bending the rail supporting base section 50 to its operative plane with respect to the other members of the joint bar. Fig. 3 is a side elevation of a portion of the said folding machine, portions being broken away. Fig. 4 is an end view of a continuous 55 type of rail joint, the joint bars of

which are adapted to be produced by the hereindescribed process, the view indicating by dotted lines the position of the base section before being folded into its operative plane by the folding machine or other suitable means. Fig. 5 is a side elevation of a rail joint with one of the joint bars removed, to expose the central crowned or raised portion of the other bar at the center of the joint. 60

The billet or bar blank that is taken up for final development by the present invention is subjected to a series of roll-passes of known form and which secure the progressive distribution and reduction of the 65 metal, and the gradual shaping of the bar, until it reaches a form substantially that of its final cross-section, wherein the bar includes the main splice member *a* having a flange member *f* and an integral rail-supporting base section *b* formed simultaneously with the flange member and rolled at an angle to its normal operative plane with respect to said main splice member *a* of the bar, as may be best seen from Fig. 2 of the 70 drawings. In substantially this design, the metal bar, which is being handled in the rolling mill, is taken up by the present process and subjected to the action of passes formed between a pair of finishing rolls *A* 75 and *B*. For the purposes of the present invention these finishing rolls *A* and *B* are designed and constructed to provide between them two passes designated respectively by the reference letters *L* and *F*, the 80 pass *F* being the final or finishing pass and the pass *L* being the next preceding pass and the last of the regular series of passes to develop a bar having the design of the 85 conventional continuous type of rail joint 90 bar. 95

The portions of the pass *L* which conform respectively to the design of the splice member and base section of the bar are designated by the reference numerals 1 and 2, and similar reference numerals designate corresponding portions of the final pass *F*, but it will be observed that these portions of the pass *L* are considerably wider than those of the pass *F* so that the splice member and base section of the bar as it enters and leaves the next to the last pass *L* are considerably thicker than the corresponding parts of the bar as it leaves the final pass *F*. Accordingly, there is a very consider- 100 105 110

able reduction or "breaking down" in the section of the material in its progressive and final development by the pass F.

The next to the last pass L of the finishing rolls distributes and prepares the material for resisting, as well as adapting itself to, the deforming, reducing, and final shaping action of the pass F, and in this connection it may be observed that the width of 10 the section 2 of the pass L is somewhat greater than the total thickness of the base section of the rail joint bar where it forms a seat or support for the ends of the rails.

The outer or bottom face of the base section b of the joint bar is intended to be flat 15 and horizontal throughout. This is provided for in both of the passes L and F by having the corresponding faces 3 of the pass sections 2 flat and uniform throughout, 20 though disposed obliquely or at an angle corresponding to the angular disposition of the base section b as it is formed in the rolls. However, in the final pass F a very radical treatment of the inner or upper face of the 25 base section b of the bar takes place. This action involves a very great reduction in the thickness of the said base section at intervals to produce a central crowning portion c for each joint bar length, which central crowning 30 portion constitutes a seat and support for the rail ends at the central part of the joint as clearly shown in Figs. 4 and 5 of the drawings. To accomplish this reduction, distribution of the metal, and shaping 35 in and on the upper face of the base section of the bar, one of the rolls, A, is provided with a die ring, designated as a unit by the reference numeral 4, and whose circumference is formed with a series of relatively 40 long die projections 5, and a series of forming recesses 6 alternating therewith. The effect of this construction is for the die projections 5 to break down or reduce the thickness of portions of the base section of the 45 bar being rolled, while the forming recesses 6 only effect a slight reduction in other portions of the base section, leaving such other portions raised or elevated above the depressed portions and thus producing on one 50 side or face of the base section the crowning portions which constitute the central rail seats c of the joint bar lengths. In Fig. 1 of the drawings, the full and dotted lines at one side of the pass section 2 respectively 55 designate the action of the depressed and raised portions of the die ring 4 on the inner or upper face section b of the joint bar.

In constructing rolls to carry out the operation above described, the depressions or 60 forming recesses 6, of one of the rolls are equally spaced around the circumference thereof in such manner that the center of one of such recesses to the center of the next adjacent one is equal to the length of the 65 standard rail joint, inasmuch as joint bars of

the character described can only be rolled in rolls whose circumference is a multiple of the length of the standard joint. Hence, the line of severance of the bar into rail joint lengths necessarily occurs at approximately 70 the center of the said recesses, or in other words, at approximately equal distances from the rail seating projections, and in this connection it will be further observed that since the bar is delivered from the final pass 75 with the base member "open," shears may be employed for cutting the bar into rail joint lengths. Also it may be noted that in carrying out the rolling operation of the final pass F, the "drag" of the material in passing 80 through the rolls may require a special shaping of the recesses 6, but these and similar details of manufacture may obviously be resorted to without affecting or departing from the process of the present invention. 85

The cross section of the rail joint bar as it comes from the final pass F of the finishing rolls is plainly shown in Fig. 2 of the drawings and has already been described. In this form the base section b of the joint bar is 90 disposed at an angle to its normal operative plane, but has completely developed and formed upon the inner or upper side thereof the central crowning or raised part c constituting the rail seat and support for the ends 95 of the rails, the remaining portions d (see Fig. 5) of the base section being normally out of contact with the rail, thus providing a theoretically correct crowning base support for the rails. Therefore, to give the 100 joint bar its final operative form, it is only necessary to bend or fold the finished base section b into its operative plane. This can be done by various expedients, such as heavy rollers, bulldozers, various types of presses 105 acting in various directions, or by other and like methods, so for illustrative purposes I have shown in Figs. 2 and 3 of the drawings a folding machine or press that may be employed for the final step in the process. This 110 machine includes an anvil 7 fitting the outer side of the joint bar, a movable clamp 8 engaging the inner side of the joint bar, and a vertically moving ram or plunger 9. The clamp 8 forms a part of the anvil and is provided on its upper side with a clearance depression 10 adapted to receive the crowned portion c of the base section b when the latter is folded or bent down to its horizontal 115 operative plane through the action of the 120 ram or plunger 9 thereof. It will be understood that before placing the bar section in the folding machine or press the same may be first reheated. 125

I claim:—

1. A process of making crowned-base joint-bars, which consists in subjecting a metal blank to a roll pass to produce a bar having a splice member in its final shape, and a base member of unfinished shape, then 130

effecting an unequal redistribution of the metal in the base member to thereby recess one face only thereof and leaving projections of metal between the recesses, and subsequently transversely severing the bar at approximately the centers of said recesses.

2. A process of making crowned-base joint-bars, which consists in subjecting a metal blank to a roll pass to produce a bar having a splice member and a flange member of finished shape and a base member of unfinished shape, said flange member and base member being separated to leave a groove therebetween, then unequally redistributing

the metal in the base member to thereby recess one wall only of said groove in alternate areas and leaving projections of metal between the grooves, subsequently transversely severing the bar at approximately the centers of the recesses, and then moving the said base member to a final position nearer the flange member.

In testimony whereof I hereunto affix my signature in the presence of two witnesses.

BENJAMIN WOLHAUPTER.
